(57) **CLAIM**

The ornamental design for a dog house, as shown and described.

DESCRIPTION

FIG. 1 is a perspective view of a dog house;

FIG. 2 is a right side elevational view thereof, the left side elevational view being a mirror image thereof;

FIG. 3 is a top plan view thereof;

FIG. 4 is a front elevational view thereof; and,

FIG. 5 is a rear elevational view thereof.

The dashed lines shown in the drawings represent stitching and form part of the claimed design. The shading indicates a leather-like surface treatment.
